UNITED STATES PATENT OFFICE.

ALFRED M. MARTIN, OF CHICAGO, ILLINOIS.

BINDER.

Application filed March 5, 1927. Serial No. 172,980.

These improvements have their more particular relation to book-type devices usually called binders, and to such thereof as have a pair of back members hinged together, 5 with covers or lids hinged to the back members respectively, and with prongs carried by the back members for holding the leaves or sheets in the device for ready removability.

This application is a continuation in part 10 of my copending application Serial No. 150,668 filed November 26, 1926 on supporting means for book-type binders, this continuation being principally with respect to subject matter disclosed by Figs. 10, 11, and 12 of 15 said copending application.

In this connection I refer also to my copending application Serial No. 169,157 filed February 18, 1927, on multiple unit book holders.

20 The prime objects of the present invention are to simplify and render more easy and satisfactory the use of such binders, saving time and labor, and thereby also increasing the efficiency of such devices. More specific 25 objects are to provide such results through means carried by the binder itself for supporting the middle portion of the book or binder when open whereby its back members may be operated on their hinge connections 30 to separate the prongs laterally to various extents in the normal operation of the book. Other objects are to provide such results while preserving the general form and shape 35 of the book or binder, and to provide supporting means which are not likely to mar the table top on which the device is used. Other objects are to provide supporting means for the purposes specified which are simple in construction, which are strong and 40 durable, which are easily to be operated, and which are highly efficient.

Still other objects and advantages will appear from the following description and the appended claims.

45 The loose-leaf binders having these improvements will ordinarily be devices of substantially large size, say ranging from thirteen to twenty inches in length, meaning in the direction of the hinge connection of the backs, and from say two to three inches in thickness and up to twenty inches in width. When substantially filled with card or sheet material such books are quite heavy.

Prior to my inventions for supporting the middle portion of the binder when open so 55 that the backs may be operated freely the practice has been to place the binder on the top of a desk, table or the like and spread the lids and leaves therein apart book-fashion for consultation or preparatory to the 60 operations necessary for removal or insertion of sheets. For these sheet-manipulating operations a latch uniformly present is released permitting the back members to swing away from each other on their hinge connections 65 whereby the opposed prongs carried by the back members are also spread apart. In the frequent turning from one place to another in the book, as for the removal or 70 insertion of sheets, it has been necessary, from the practical standpoint, to raise and swing from side to side to various extents one of the covers, together with all of the 75 cards or sheets on it, the operator either thus closing the backs together completely until 80 caught and held, or partially, by holding one side of the book in raised position so that the prongs will overlap, cards or sheets being swung from one set of prongs to the other while one side is thus held. In view of the 85 weight of the parts thus manipulated the operation involves the expenditures, especially during the entire day, of a large amount of energy, and these books are to a large extent handled by women.

In my said copending applications I have shown various means for overcoming the disadvantages of the ordinary methods of manipulation by supporting the middle portion 90 of the book. All of the advantages of the book holders described in said first-mentioned copending application are to be had from the present device, together with other advantages, since according to the present device separate holding means are not necessary and the binder as a whole is always ready for use and for use according to a simple method of operation thus made possible.

It may be mentioned also that the book or 100 binder formed according to the preferred construction of this application is quite as susceptible of use in the multiple unit book holder of said second-mentioned copending application as are binders of the type illustrated in that copending application. The 105

device of the modified construction shown herein is not suitable to be used in said multiple unit holder.

Figure 1 of the drawings is an elevation of the preferred form of my improved binder in what may be termed a back view—that is, directly toward the back members from the outside; Fig. 2 is a fragmentary side elevation of the device of Fig. 1, parts of the 5 lids or covers being broken away; Fig. 3 is a front end view of the same binder with the lids spread apart and only fragmentarily shown, other parts of the device being broken away to show interior constructions; Fig. 4 is a fragmentary enlargement of parts 10 including the dotted-line portion of Fig. 2, walls being broken away. It shows the spring and catch elements for holding one of the swinging book-supporting members; Fig. 5 is a fragmentary face view, and Fig. 15 20 is an edge view of a metal frame piece having the catch element formed therefrom and carried thereby; Fig. 7 is an end view of the binder, with the lids broken away, 25 showing the book-supporting members spread apart, the latch for the back members being released and the back members being spread apart slightly; Fig. 8 shows the device of Fig. 7 with the back members elevated to their full extent and the prongs 30 thereby spread widely apart; Fig. 9 is a front end view of a modified form of construction, the lids being partly broken away; and Fig. 10 is an end view similar to that of Fig. 7 showing the supporting members of 35 the device of the modified form spread apart, the latch for the back members not, however, being released.

Like parts of the preferred and modified forms will be similarly marked on the drawings.

Describing first the fundamental binder parts illustrated the construction comprises a pair of back members A and B hinged together at 12. The finger-piece 13 controls the latch of which the member 14 (Fig. 8) is a part, and when the backs are closed as in Fig. 3 the latch holds them firmly yet releasably together. The back members include the side walls 15 which carry the prongs 16 respectively, which prongs, in the specific type of binder shown, overlap each other in the closed relative position and in the partly open relative positions of the back members. These side walls 15 terminate in hinge knuckles at 17 and on the hinge pins thereof are covers 18 respectively.

More specific description of the construction of the fundamental binder parts is not necessary since what is illustrated in this respect is well known, and, furthermore, the present invention is not concerned with specific constructions of the binder, but rather with the type of binder involved. 60 This type may be described as comprising

a pair of back members movable relative to each other, and ordinarily hinged to each other, with prongs carried by the back members to move in directions toward and away from each other when the back members are moved relative to each other, a lid or cover being flexibly connected to each back member.

It has been customary in connection with binders of the type illustrated to cover the back members with various kinds of material, the most preferred being fibre in sheet form and approximately one-eighth of an inch thick. Such fibre has extended longitudinally as a continuous piece from end to end of the backs, and transversely from closely adjacent to the central hinge 12 to the hinges 17 respectively, the material being formed to fit the shape of the back member in cross view and being firmly and permanently secured to the back members as by rivets. Some such rivets are shown at 20 in Fig. 1 where they hold strips 21 of such covering material permanently upon the backs respectively.

In the particular embodiment of the present invention shown I utilize for my book-supporting members portions of such back-covering material, chiefly the side portions thereof, but the invention is not limited to such construction.

Referring to Figs. 7 and 8, each supporting member 22 comprises first a metallic plate 23 extending longitudinally the full length of the back member and having hinge knuckles formed on it for engagement with the hinge pin at 17. In Fig. 2 some of the hinge knuckles as 24 may be considered to be part of the metal piece 23, the hinge knuckles as 25 as being carried by the back member 15, and the intervening hinge knuckles as 26 as being connected to the cover 18. A single hinge pin at 17 therefore holds these three members together. The metal piece 23 is bent approximately at right angles to provide the inwardly-extending part 23^a which, as shown by Fig. 3, overlies the outer edge portions of the permanently secured strip 21 of covering material. On this metal piece 23 is applied covering material 27, suitably fibre, formed at the bottom to turn inward at 27^a, so as to lie upon the metal part 23^a, and this covering 27 is firmly riveted to the metal part 23 by rivets 28 (Fig. 2).

The extensions 27^a have their corners cut away at 29 and are slightly rounded there so as to present a suitable surface to the table top or the like on which the device is ordinarily used. These extensions 23^a—27^a 125 constitute feet, and the connecting parts 23—27 constitute legs or leg-like members for supporting the middle portion of the book when open.

I provide means for holding for ready 130

releasability these laterally-swinging supporting members 22 against the side walls 15 of the back members respectively. The preferred catch means for this purpose are 5 well shown in Fig. 3 as comprising a spring 32 bent somewhat U-shaped and provided with a tongue at 33 at one end passing through a hole in the upper wall of the frame, the bend of the spring at 34 being seated against the inner wall of the back member, the normally lower and free end of 10 the spring having a bead or turn 35 thereon fitting into the corner between side and bottom wall members of the back member 15 frame. The hollow part of the back member is ordinarily called boxing, and the spring 32 is within the hollow interior of this boxing and is held therein against the 20 possibility of getting out of proper operative position by the construction and arrangement shown. It is put in there at the time the boxing is closed.

Figs. 7 and 8 plainly show the catch member 36 adapted to cooperate with the 25 spring 32. Figs. 5 and 6 show how this catch member may conveniently be formed out of the metal piece 23, as by merely punching it out on, roughly speaking, three sides, leaving it attached at the fourth and 30 bending it up at right angles. Fig. 4 shows at 38 a fairly wide opening in the side wall 15 of the back member and also that at 39 the bottom covering piece 21 is also somewhat cut away, and these openings are 35 made to permit the free end of the catch member 36 to come into engagement with the head or roll 35 of the spring 32.

Fig. 3 shows that in moving the swinging member 22 into locked position the slanting surface 36^a on the catch 36 will push the bead 35 upward as the parts are viewed in 40 Fig. 3 and that thereupon this bead 35 will descend into the seat recess 36^b (see Figs. 7 and 8 for the reference numbers) and thus hold the swinging member 22 against the side wall 15 of the back member. The swinging supporting member 22 may be released from the holding effect by simply forcing it in the outward direction, which 45 may readily be done and with little expenditure of energy. With the side members so held the book may be handled in the ordinary ways and the conventional appearance is maintained, the only substantial difference in appearance being that the feet 50 27^a overlap the covering members 21 respectively at the corners. This is not objectionable, but rather improves the appearance. It also improves the strength of the book at 55 these corners where they receive their severest knocks. Such overlap by the feet as 27^a is not necessary, however, since the arrangement shown in Figs. 9 and 10 in this respect could be used as well.

60 Fig. 3 shows how the book may be opened

for such purposes as consultation or to make some entries at given places without removing or inserting sheets or performing any other manipulations calling for relative movement of the prongs. Fig. 7 shows 70 the laterally-swinging supporting members 22 spread in directions apart and the latch controlled by the finger-piece 13 released, permitting the backs to open. The position of Fig. 7 is one which may be maintained as 75 the basic position for operations all day long, avoiding all use of the lock for the back members until time to put the book away.

To swing the members 22 in directions apart the most convenient method is to apply the thumbs upon the lids or covers 18 and grasp the feet 27^a with the tips of the fingers and simply draw these swinging members outward, and for this convenient method of operation the binder as a whole 80 will be drawn toward the operator so that the front end thereof will be free of the table top slightly. The thumbs may be applied, however, directly to these side members 22 to force them apart. The supporting members as 22 will be spread apart as 85 the first operation before releasing the latch by the finger-piece 13 when the book is in the position of Fig. 3.

Note from Figs. 7 and 8 how the supporting members 22 impinge against the lids 18 adjacent to the hinge connection at 17. The covers 18 as well as the covering material on the supporting members 22 is beveled to such an extent as to permit the legs to swing 90 apart to form a substantially wide base, further lateral movement being stopped when the predetermined spread is attained.

Fig. 8 shows the backs A and B of the modified construction raised to their full 105 extent and with the prongs 16 (partly broken away) so widely separated that sheets or leaves on them may simply be slipped off and away. From the position of Fig. 8 the backs may easily be lowered to 110 any extent desired, by simply pressing them down, so as to bring the prongs into overlap, for instance as in Fig. 7, whereby sheets may be swung from one side to the other of the book. Then at any particular place 115 among the sheets the backs may be again raised to insert or remove sheets or perform any other manipulations, for example shifting one back member relative to the other, as in what are known as shift binders of 120 this type.

When the book contains the usual quantity of sheets or leaves (the sheet material preferably not unduly filling or overfilling the book, especially in the thinner sizes) the 125 back members remain at various elevations with respect to the table top, including the fully-raised position of Fig. 8, into which they are moved while being supported by the members 22. It is pointed out also that 130

all of the sheet material may be on one side without rocking the backs on the hinge connection between them or moving the middle portion of the book bodily off its support. 5 The construction as a whole is quite stable, and there is no possibility of a lateral collapsing tilting action of the supporting structure when the book is unlocked and open in the normal operations and the supporting members are normally spread apart. 10 The hinges at 17 remain in their normal substantially horizontal plane, and this regardless of how the sheet material may be disposed, for example all on one set or series of 15 the prongs. In the appended claims where I refer to lateral tilting movements I mean such movements as would result in a collapsing or falling down of the supporting structure when the supporting means are in normal position for use and the book is open. 20

In Fig. 9 the laterally-swinging supporting members 40 are pivotally mounted at 41 adjacent to the hinge connection 17 on the lid member 18. Their respective feet 40^a 25 abut the side edges of the covering elements 42 respectively, thus preserving the usual contour of the covering on the backs. When the lids 18 are swung in directions apart the supporting members 40 are moved relative to the back members whereby the latter are elevated when the feet 40^a are resting on the table top. Fig. 10 shows the middle of the book elevated considerably, due to the distance between the pivots 17 and 41 at 35 each side. In some constructions of binders it may be advantageous to raise the back portions somewhat for ensuing manipulations. The principal objection to this modified construction of Figs. 9 and 10 is that the 40 lids and sheets between them may not be swung from side to side without, in some movements, swinging the supporting members also, and this construction is not therefore adapted for use in the multiple unit 45 device of my said secondly-mentioned co-pending application.

I conceive the present invention to be broad in scope, and am therefore claiming it herein with a view to various changes, departures and modifications possible in kinds and characters of construction and arrangement from what is thus specifically set forth.

I claim:

1. In a loose-leaf binder, the combination 55 of a pair of back members movable relative to each other, prongs carried by the back members respectively so as to move toward and away from each other when the back members are moved relative to each other, a cover flexibly connected to each back member, and supporting members carried by the binder and mounted thereon for movement into binder-supporting position for supporting on a rest surface the middle 60 portion of the binder when in an open posi-

tion for use while maintaining the back members free to be moved relative to each other to move the prongs in the normal operations of the device.

2. In a loose-leaf binder, the combination 70 of a pair of back members movable relative to each other, prongs carried by the back members respectively so as to move toward and away from each other when the back members are moved relative to each other, a 75 cover flexibly connected to each back member, and leg-like members pivotally carried by the binder to spread apart at their normally lower ends to form a substantially wide base for supporting on a rest surface 80 the middle portion of the binder when in an open position for use while maintaining the back members free to be moved relative to each other to move the prongs in the normal operations of the device. 85

3. In a loose-leaf binder, the combination 90 of a pair of back members movable relative to each other, prongs carried by the back members respectively so as to move toward and away from each other when the back members are moved relative to each other, a cover flexibly connected to each back member, and laterally-swinging members having 95 their normally lower ends free and having a limited lateral spread at their normally lower ends carried by the binder at the flexible connections of the covers with the back members respectively for supporting on a rest surface the middle portion of the binder when in an open position for 100 use, while maintaining the back members free to be moved relative to each other to move the prongs in the normal operations of the device. 105

4. In a binder of the character described, the combination of a pair of back members hinged together and having longitudinally extending side walls facing each other when the back members are in closed position, prongs carried by the side walls of the back 110 members, the prongs being directed toward the opposite side walls respectively, a cover flexibly connected to each back member, and means carried by the binder for supporting firmly and against lateral tilting movements the middle portion of the binder when open, while maintaining the back members free to move with respect to each other on the hinge connection between them. 115

5. In a binder of the character described, the combination of a pair of back members hinged together, prongs carried by the back members, a cover flexibly connected to each back member, and members pivotally carried by the binder for supporting firmly and against lateral tilting movements the middle portion of the binder when open while maintaining the back members free to move up and down while moving relative to each other on the hinge connection between them. 120 125 130

6. In a binder of the character described, the combination of a pair of back members hinged together, each back member having outer boxing covering forming outer corners, prongs carried by the back members, a cover flexibly connected to each back member, and means comprising leg-like members carried by the binder at places respectively spaced from said corners for supporting firmly and against lateral tilting movements the middle portion of the binder when open while maintaining the back members free to move on the hinge connection between them. 10
7. In a binder of the character described, the combination of a pair of back members hinged together, prongs carried by the back members, a cover flexibly connected to each back member, and a plurality of supports carried by the binder and arranged to be moved severally and individually into relative positions providing a substantially wide base for the middle portion of the binder when open. 20
8. In a binder of the character described, the combination of a pair of back members hinged together, prongs carried by the back members, a cover flexibly connected to each back member, and supporting members pivotally mounted on the binder to move in directions apart at their normally lower portions to form a firm and substantial base for the middle portion of the binder when the binder is normally open and resting on a substantially flat surface. 30
- 35 9. In a binder of the character described, the combination of a pair of back members hinged together, prongs carried by the back members, a cover flexibly connected to each back member, and supporting members mounted to swing at their normally lower ends in directions apart on normally horizontal axes respectively when the binder is normally to be opened and placed on a substantially horizontal rest surface. 40
- 45 10. In a binder of the character described, the combination of a pair of back members hinged together, prongs carried by the back members, a cover flexibly connected to each back member, and a pair of leg members pivotally mounted on the binder approximately at the hinge connections between the back members and the lids respectively to spread in directions away from each other at their normally lower ends to form a substantially wide base for the binder when open and resting on a table top or the like. 50
- 55 11. In a binder of the character described, the combination of a pair of back members hinged together, prongs carried by the back members, a cover flexibly connected to each back member, and supporting members extending substantially from end to end of the binder and mounted on the binder at places adjacent to the flexible connections between the covers and the back members respectively to swing in directions apart at their normally lower end portions to form a base for the middle portion of the binder when open and resting on a table top or the like. 60
12. In a binder of the character described, the combination of a pair of back members hinged together, prongs carried by the back members, a cover flexibly connected to each back member, and supporting members carried by the binder at the hinge connections between the covers and the back members respectively and being adapted to be spread in directions apart at their normally lower end portions and form a base for holding the middle portion of the binder whereby the back members may move up and down while moving relative to each other on the hinge connection between them and while the middle of the binder is firmly supported. 70
13. In a binder of the character described, the combination of a pair of back members hinged together, covering members for the back members positioned at the sides of the back members respectively, prongs carried by the back members, a cover flexibly connected to each back member, said covering members being pivotally mounted on the hinges between the back members and the covers respectively and being adapted to be spread in directions apart at their normally lower ends to a limited extent to form a substantially wide base for the middle portion of the binder when open. 80
14. In a binder of the character described, the combination of a pair of back members hinged together, covering members for the back members positioned at the sides of the back members respectively, prongs carried by the back members, a cover flexibly connected to each back member, said covering members being pivotally mounted on the hinges between the back members and the covers respectively and being adapted to be spread in directions apart at their normally lower ends and to a limited extent to form a base for the middle portion of the binder when open, and means for holding said covering members releasably in closed position. 90
15. In a binder of the character described, the combination of a pair of back members hinged together, prongs carried by the back members, a cover hinged to each back member, and supporting members normally extending longitudinally alongside of the back members respectively and being hinged at the hinges between the covers and back members respectively to be spread in directions apart at their normally lower ends and to a limited extent for supporting on a rest surface the middle portion of the binder when open while maintaining the back members free to be moved up and down to open and close them to various extents in the normal operation of the device. 100
- 110
- 115
- 120
- 125
- 130

16. In a binder of the character described, the combination of a pair of back members hinged together, prongs carried by the back members, a cover hinged to each back member, and supporting members normally extending longitudinally alongside of the back members respectively and being hinged at the hinges between the covers and back members respectively to be spread 5 apart at their normally lower portions for supporting on a rest surface the middle portion of the binder when open while maintaining the back members free to be moved up and down to open and close them to 10 various extents in the normal operations of the device, said supporting members having inturned edge portions serving as feet.

17. In a loose-leaf binder, the combination of a pair of back members movable 20 relative to each other, prongs carried by the back members respectively so as to move toward and away from each other when the back members are moved relative to each other, a cover flexibly connected to each back member, and leg members hingedly carried by the binder at the hinge connections between the backs and the covers respectively and being mounted to be spread in directions apart at their normally lower 25 portions to an extent sufficient to provide a substantially wide base for supporting on a rest surface the middle portion of the binder when in an open position for use while maintaining the back members free 30 to be moved relative to each other to move the prongs in the normal operations of the device.

18. In a loose-leaf binder, the combination of a pair of back members pivotally 40 movable relative to each other, series of prongs carried by the back members respectively so as to move toward and away from each other and overlap each other in side by side relation and to come out of such 45 overlapped relation when the back members are moved relative to each other, a cover flexibly connected to each back member, and supporting members mounted at the flexible connections between the covers and the back 50 members respectively and adapted to be spread in directions apart at their lower end portions and to impinge against the covers respectively when in spread-apart relation for supporting on a rest surface the middle 55 portion of the binder when in an open position for use while maintaining the back members free to be moved relative to each other to move the prongs in the normal operations of the device.

19. In a loose leaf binder, the combination of a pair of back members hinged together, prongs carried by the back members, a cover flexibly connected to each back member, and means carried by the binder close to the flexible connections between the 60 covers and the back members respectively providing a firm, stable and non-tilting support for holding the middle portion of the binder when the binder is open and resting on a substantially horizontal surface 65 whereby the back members may be moved up and down and relative to each other on the hinge connection between them while maintaining the flexible connections between the covers and the back members 70 respectively in substantially the same horizontal plane.

20. In a loose-leaf binder, the combination of a pair of back members operatively connected together for movement in directions away from and toward each other, prongs carried by the back members respectively so as to move away from and toward each other for the removal and insertion of sheets when the back members 80 are so moved, a cover flexibly connected to each back member, oppositely-disposed members with laterally-extending ends carried by the binder and adapted to assume 85 downwardly and outwardly extending positions for supporting the middle portion of the binder firmly and against lateral 90 tilting movements when the binder is in an open position for use on a table top or the like.

21. The combination with a binder of the character described having a pair of back members hinged together and a stiff and substantially heavy and wide cover in hinged relation to each back member, of 95 means forming a rigid support held in rigid position lateral of each back member and cooperating with said covers respectively and engaging the binder adjacent to the hinge connection between the covers and the back members respectively for holding the back members suspended from places on the binder adjacent to the hinge connection between the covers and back members respectively for free up-and-down movements on the hinge connection between the back members while maintaining the middle portion of the binder against lateral-and-downward collapse when the covers are 100 spread apart and the binder is so supported 105 and normally in use.

ALFRED M. MARTIN.
